UNITED STATES PATENT OFFICE

157,575

BOX

Robert B. Edelmann, Chicago, Ill.

Application March 31, 1948, Serial No. 145,461

Term of patent 7 years

(Cl. D58—12.6)

To all whom it may concern:

Be it known that I, Robert B. Edelmann, a citizen of the United States, and a resident of Chicago, in the county of Cook and State of Illinois, have invented a certain new, original, and ornamental Design for a Box, of which the following is a specification, reference being had to the accompanying drawing, forming part thereof.

I claim:

The ornamental design for a box, substantially as shown.

ROBERT B. EDELMANN.
